UNITED STATES PATENT OFFICE

CHARLES W. BALLARD, OF NEW YORK, N. Y.

FASTENING FOR SAMPLE ENVELOPES.

SPECIFICATION forming part of Letters Patent No. 258,348, dated May 23, 1882.

Application filed August 6, 1881. (Model.)

To all whom it may concern:

Be it known that I, CHARLES W. BALLARD, of the city, county, and State of New York, have invented a new and Improved Fastening 5 for Sample Envelopes, of which the following is a specification.

The object of my invention is to provide a new and improved fastening for sample envelopes, with which the envelope can be opened 10 or closed and secured very rapidly and conveniently, which can be used repeatedly without injury to the envelope or the fastening, and, finally, which cannot be opened accidentally.

15 The invention consists in a longitudinal metal strip provided with an open hook at its upper end, a closed hook at its lower end, and a projecting metal tongue opposite the lower end of the open hook, which strip is secured on the back of the envelope, the perforated flap of which is hooked on the open hook.

In the accompanying drawings, Figure 1 is a 20 perspective view of a sample envelope provided with my improved fastener. Fig. 2 is a longitudinal sectional elevation of the same, showing the flap raised on the line xx , Fig. 1. Fig. 3 is a longitudinal sectional elevation of a modification, showing the flap closed on the line xx , Fig. 1; and Fig. 4 is a perspective view 25 of the detached metallic strip.

The end flap, A, of an envelope, B, is thickened and strengthened by doubling over the paper at the end of this flap and pasting it on the inner surface of this flap; or the flap can 30 be strengthened or thickened by pasting on a detached piece of paper or in some other suitable manner. This flap A is provided with a perforation or aperture, C, near its end or outer edge, a longitudinal metal strip, D, provided with an open hook, E, at its upper end, and a closed hook or tongue, F, at its lower end, and a tongue, G, opposite to the end of the upper hook, E, is secured in the back of the envelope B in such a manner that the flap A can 35 be turned down over the hook E, which can be passed into the aperture C. The strip D is punched out in such a manner that tongues E', F', and G, at right angles to the same, will be formed at the ends and a short distance

from the upper end, as shown in Fig. 4. This strip is passed into the inside of the envelope, and the tongues are forced through the back of this envelope; and at the same time the upper tongue, E', is bent over downward to form the open hook E, and the lower tongue, F', is bent down flat on the back of the envelope to form the closed hook F, which holds the strip D to the envelope. The tongue G preferably remains erect, as shown in Fig. 2, but can be bent down to assist holding the strip on the envelope, as shown in Fig. 3.

If the envelope is closed, as shown in Fig. 2, it can only be opened if the flap A is raised against the under side of the hook E and then pushed downward, and it is evident that this flap cannot be opened accidentally, for if the flap is only pushed down, but not properly raised, it will strike the tongue G and cannot be opened.

The envelope can be opened and closed very 70 rapidly and conveniently without bending and twisting any parts.

This envelope is especially designed for samples, documents, printed matter, &c., which must be examined by the post-office officials, 75 and this examination is greatly facilitated by this envelope.

The envelope can be made of any suitable material. The flap will remain closed, even if the tongue G is folded down; but the fastening will be better if the tongue G remains raised.

The hook may be fastened in the flap and the back of the envelope may be perforated—that is, the construction shown may be reversed. 85

Having thus described my invention, I claim as new and desire to secure by Letters Patent—

The combination, with an envelope, B, provided with a perforated flap, A, of a metal strip, D, provided with an open hook, E, a closed hook, F, and a tongue, G, substantially as herein shown and described, and for the purpose set forth.

CHAS. W. BALLARD.
